UNITED STATES PATENT OFFICE.

RAYMOND F. AYERS AND ELIOT KEEN, OF NEW YORK, N. Y.

TOY.

No. 828,995.

Specification of Letters Patent.

Patented Aug. 21, 1906.

Application filed October 20, 1905. Serial No. 283,614.

To all whom it may concern:

Be it known that we, RAYMOND F. AYERS and ELIOT KEEN, citizens of the United States, and residents of New York city, in the county of New York and State of New York, have invented certain new and useful Improvements in Toys, of which the following is a specification.

Our invention relates to a toy of the paper-cut-out type, and more especially to a mechanical arrangement for imparting motion to such devices.

We will describe our invention in the following specification and point out the novel features thereof in claims.

Referring to the drawings, Figure 1 is a side elevation of a toy made according to our invention. Figs. 2, 3, 4, and 5 illustrate patterns of one form of cut-out which may be printed upon paper, cardboard, or other suitable material. Fig. 6 is a perspective view of the arrangement which we have invented for imparting motion to figures of this kind. Figs. 7, 8, and 9 are side elevations of the cut-out with the parts in different relative positions, illustrating the operation of the invention.

Like characters of reference designate corresponding parts in all of the figures.

10 designates a figure having parallel sides 11 and 12, preferably formed from a blank of paper, cardboard, or other suitable material. It may be made to represent a figure such as that of a person, animal, or object, such, for example, as a goat-carriage, as shown in the drawings. Fig. 2 shows a blank with a fancy figure printed upon it. We will describe somewhat specifically the figure therein shown for the purpose of illustrating our invention, but do not limit ourselves in any way to this particular shape or design. The figure may be printed upon a flat card, upon which may also be printed directions for cutting out, setting up, and operating the toy. 45 The sides 11 and 12, which when the object is set up should be parallel to each other, represent the sides of a cart having wheels 13 13 integral therewith. The portions 14 14 will form the front end of the cart, and the portions 15 15 will form the rear end of the cart. 50 16 16 designate a harnessed goat attached to the cart. A number of projecting lugs 17 are provided. The dotted lines designate lines on which the figure is to be folded. Four 55 slits 18 should be cut in the portion which forms the top of the cart, and small holes 19

19 should be made in the sides 11 and 12 in the places designated. The figure may be cut out and folded upon the dotted lines. Paste may be applied to lugs 17, which are 60 shown with their surface shaded, and these may be struck fast to the inside of the cart. The two portions 16 16 should also be pasted together. The figure when thus cut out and set up will form an object like that shown in Fig. 1.

A small figure, such as that of a kneeling boy 20, (shown in Fig. 4,) may be cut out, with extensions 21 21 attached thereto. These extensions should be bent at the dotted 70 lines at right angles to the rest of the figure, and these may be slipped through the slits 18 18 on the top of the cart, so that the figure of the boy will appear as it is shown in Fig. 1. Fig. 5 illustrates a similar figure 30 of a child 75 in a sitting posture. This figure is provided with extensions 31, and it may be used in the manner above described. It is evident that as many of these figures as desired may be provided and that one or more of them may 80 be used at once. Fig. 3 shows another pattern printed upon a similar blank. After it is cut out the shaded portion 41 should be pasted upon the portion 42. The extending portion 43 may also be bent over and pasted 85 down upon the main portion of this piece. When completed, this will form an oblong ring 40, as shown in Fig. 6. This ring should be formed to have flat portions on the sides where the parts 41 and 42 are pasted together 90 and where the portion 43 is pasted down and to have its ends 44 and 45 semicircular in shape. The width of this ring 40 is slightly greater than the length of an ordinary thread-spool 50, and the width of the top of the cart 95 or the distance between the parallel sides 11 and 12 is slightly greater than that of the ring 40.

We will now describe the operation of the device. After the figure has been set up, as 100 previously described, a round body of suitable size and form, such as an ordinary spool 50, is placed within the ring 40, the latter is placed between the parallel sides 11 and 12 of the completed figure, and a pin 60 put 105 through the holes 19 and ring 40. The toy is then placed upon a board or other suitable support 70. Motion is imparted to the toy by tilting the support 70, as shown in Fig. 7. The spool 50 will first run down in ring 40 110 until it reaches the semicircular portion 44. During this part of the operation the cart

itself will have little or no motion. The spool will continue its onward movement, and the ring 40 will then roll with it. This will cause the ring 40 to be brought into the position shown in Fig. 8, with its side pressing against pin 60. This will carry pin 60 and the whole object upward and forward in the direction indicated by the arrow. The forward part of the object—for example, the goat 16—may be designed to touch support 70 when the parts are in this position. As spool 50 and ring 40 roll along they come into the positions shown in Fig. 9, carrying the object forward, but the ring 40, acting upon pin 60, again bringing the rear portion of the object down onto support 70. This cycle of operations will be repeated. The intermittent forward and up-and-down movement thus imparted to the toy much resembles that of a galloping horse or of a jumping rabbit. It is not necessary for ring 40 to have flat sides. It may be elliptical in form, if desired. Of course this same motion may be imparted to other objects in a similar manner, and we therefore do not limit ourselves in any way to the specific application of this invention herein shown and described.

We have described this toy as a paper cut-out; but we do not limit ourselves to this construction, as of course the toy may be made of tin or other material and in any desired design.

What we claim is—

1. In a toy, the combination of a hollow object, an oblong ring within the object, and a body capable of being rolled, said body being situated within the ring.
2. In a toy, the combination of a hollow object having parallel sides, an oblong ring within the object, and a round body within the ring.
3. In a toy, the combination of a hollow object having parallel sides, a supporting-base therefor, an oblong ring within the object, a pin through said sides and through said ring, and a round body within the ring.
4. In a toy, the combination of a hollow object having parallel sides, a supporting-base therefor, an oblong ring within the object, a pin through the ring and through the parallel sides of the object and supported thereby, said ring having both of its axes longer than the distance from the base to the pin; and a round body within the ring.
5. In a toy, the combination of a body pictorially representing an object, said body

having a hollow compartment with parallel sides and a top, an oblong ring within said compartment, a pin through the ring and through the parallel sides and supported by said sides, a round body within the ring, and an independent object detachably mounted upon the top of the first object.

6. In a toy, the combination of a body pictorially representing an object, said object having a hollow compartment with parallel sides, a supporting-base therefor, one of the lower parts of said body being parallel to the supporting-base and another of the lower parts of said body being at an angle to said supporting-base, an oblong ring within said compartment, a pin through the ring and through the parallel sides and supported by said sides, and a round body of some weight within the ring.

7. In a toy, the combination of a body pictorially representing an object, said body having a hollow compartment with parallel sides, a supporting-base therefor, one of the lower parts of said body being parallel to the supporting-base and another of the lower parts of said body being at an angle to said supporting-base, an oblong ring within said compartment, a pin through the ring and through the parallel sides and supported by said sides, and a round body of some weight within the ring, said round body arranged to be rolled within said ring and to cause the ring to rock the object and to carry it forward.

8. A cut-out toy formed from a printed blank pictorially representing an object and having a hollow compartment, and propelling means within the compartment, said means comprising an oblong ring and a spool within the ring.

9. A cut-out toy formed from a printed blank, pictorially representing an object, and having a hollow rectangular compartment, propelling means for the toy within the compartment, said means comprising an oblong ring of a width less than that of the compartment and a spool within the ring of a length less than the width of the ring.

In testimony whereof we have signed our names to this specification in the presence of two subscribing witnesses.
